UNITED STATES PATENT OFFICE.

ANNA E. MARSHALL, OF NEW YORK, N. Y.

DESIGN FOR A FRAME FOR MOVING PICTURES.

No. 39,030.

Specification for Design.

Patented Jan. 21, 1908.

Application filed October 12, 1907. Serial No. 397,223. Term of patent 3½ years.

To all whom it may concern:

Be it known that I, ANNA E. MARSHALL, a citizen of the United States, residing at New York, in the county of New York and State of New York, have invented a new and original Design for a Frame for Moving Pictures, of which the following is a specification, reference being had to the accompanying drawing, forming a part thereof.

The figure is a front view of a design for a

frame for moving pictures showing my invention.

I claim:

The ornamental design for a frame for moving pictures, as shown.

ANNA E. MARSHALL.
